Application January 8, 1952, Serial No. 265,474

9 Claims. (Cl. 53—21)

This invention relates to a device and method for uncasing empty containers and for casing the same containers after the filling operations, and more particularly to the machinery and method of accomplishing such operations in a minimum of time with a minimum of personnel.

In prior machines and methods for accomplishing these results, it has been customary to have the empty containers packed in cases, right side up with the top flaps of the cartons unsealed. The cases are then delivered to the filling machine where an operator will remove the containers one at a time from the cases and manually place the containers into the filling machine. The empty case is then manually placed on a conveyor and delivered to the station where the filled containers are again packed. Another previous method of uncasing the containers is to deliver the cases of unfilled containers by pallet to the uncasing station. The containers are upside down in the cases with the top flaps of the cases open. When the containers are uncased, the case is manually turned upside down and the containers come out right side up on a conveyor which leads to an unscrambling machine. After the containers have been filled, it has been customary to manually place the filled containers back into the empty cases one at a time. Also, an empty case has been positioned underneath the conveyor and means are provided for dropping one case load at a time into the empty case through chutes. This dropping of the containers can be very detrimental to the containers since considerable damage can result during dropping. Also, in the casing operation, it has been customary to place the open side of the empty case over the containers as they come from the filling machine. However, this operation requires that the cases be turned upside down so that the open flaps can be sealed. This case turning operation can also be very damaging to the containers and to their caps. In all of the previous casing operations, the open flaps are maintained on the top of the case and the flaps are glued in this position. Therefore, the cases must be passed through a compression unit in order to keep the flaps in the closed position for the period of time necessary for the glue to set. If no compression unit is available, the open flaps can be manually closed after gluing and it is then necessary to manually turn the cases over in order to hold the flaps in position by the weight of the filled containers so that the glue will have an opportunity to set.

In order to overcome the disadvantages of prior devices and methods, the present invention utilizes cases which are delivered to the uncasing operation with both the cases and empty containers right side up and with the bottom flaps open. This arrangement makes it possible, after the two outside flaps are plowed open, for an operator to drop the empty containers out of the case onto a conveyor in condition to be unscrambled or filled in groups. A U-shaped filling and labelling line is utilized and the empty containers enter the line at one end while the filled containers leave from the other end. These ends are positioned adjacent each other so that one operator can drop the empty containers from the case and place the same case over a group of filled containers leaving the filling line. This makes it possible to have only one simple, light-weight handling operation for each case. As the

2

case is positioned over the top of the filled containers, it also operates a novel tripping mechanism which provides that only the number of containers required to fill the case will leave the line. After the case is completely positioned over the containers, novel means are provided to plow under the flaps and apply glue to the outside flaps while the case and container are still in the upright position. Thereafter, the weight of the containers will hold the flaps in position and allow the glue to set. It is readily apparent that the subject invention provides a means of quickly uncasing the empty containers and casing the filled containers. All manual handling of individual containers is eliminated as well as the manual turning of cases with their empty or filled containers. Also, all manual opening or closing of the flaps is completely eliminated by this invention as well as the need for additional case sealing equipment and compression units. The containers are not dropped and/or turned and thus there are no unnecessary strains on containers and cases during the uncasing and casing operations.

It is therefore an object of this invention to provide a device and method for uncasing and casing containers which provide for one simple, light-weight handling operation for each case. This handling operation is preferably a manual operation although it could be done mechanically.

Another object of this invention is to provide a caser and uncaser in which it is unnecessary to turn the cases and containers in order to either remove the containers from the cases or to seal the cases.

A still further object of this invention is to provide means for opening and closing the flaps of the cases during the uncasing and casing operations by purely mechanical means.

Another object is the provision of a novel tripping mechanism which provides that only the number of filled containers required to fill a case will leave the filling line.

Another object of the invention is to provide means for sealing the containers wherein the flaps are folded into position underneath the case and thereafter the weight of the containers in the case serves to hold the flaps in position to allow the glue to set.

These and other objects of the invention not specifically set forth above will become readily apparent from the specification and accompanying drawings in which:

Figure 1 is a plan view of the invention showing the relationship of the various components thereof.

Figure 2 is a perspective view of the uncaser unit of this invention illustrating the means for unfolding the flaps.

Figure 3 is an end elevational view of the uncaser unit taken in the direction of arrows 3—3 of Figure 2 illustrating the manner in which the outside flaps of the case are opened by the flap plows.

Figure 4 is a plan view of the caser unit illustrating the manner in which the filled containers are grouped for casing.

Figure 5 is a side elevational view of the caser unit showing the manner in which the cases are positioned over the top of the filled containers.

Figure 6 is an end elevational view of the side pressure conveyor unit in the direction of arrows 6—6 of Figure 4 illustrating the manner in which the inside flaps are folded under the case.

Figure 7 is a plan view of the conveyor unit along which the outside flaps are glued and folded under the case.

Figure 8 is a side elevational view of the conveyor unit in the direction of arrows 8—8 of Figure 1 illustrating the gluing unit and the flap plows.

Figure 9 is an end elevational view of the conveyor unit in the direction of arrows 9—9 in Figure 7 illustrating the manner in which the outside flaps are folded under.

Figure 10 is a schematic wiring diagram showing the power units for the various components of the subject invention.

The embodiment of the present invention chosen for illustration is shown in Figure 1 and comprises generally an uncaser unit 1 which opens the bottom two outside flaps of the case holding the empty containers and an operator 2 who pulls the case from the uncaser unit and allows the empty containers to fall onto a conveyor belt leading to the unscrambler unit 3. The caser unit 4 is positioned next to operator 2 so that the operator can place the empty case, which has just been unloaded, over the filled containers in caser unit 4. After the empty case has been placed over the top of the filled containers and pushed completely down, the case with its containers is moved by side pressure conveyor unit 5 or by gravity, and during this movement the bottom inside flaps are folded up underneath the filled containers by flap plows. The cases are then received by conveyor unit 6 which contains means for applying glue to the bottom outside flaps and for then folding these glued flaps into position under the case.

Referring to Figure 2, the rolls 7 and 8 of uncaser unit 1 receive cases from the conveyor 9 driven by motor 9'. Each case contains empty containers and has its inside and outside bottom flaps closed in the regular manner but unsealed. As the case moves onto rolls 7 and 8, the outside bottom flaps will be pressed down against the tilted rolls. The rolls 7 and 8 are tilted down toward each other a sufficient amount so that the weight of the empty containers can force the outside flaps against the rolls. The rolls 7 have their ends pivotally mounted in end channels 10 and 11 while rolls 8 have their ends similarly mounted in end channels 12 and 13. These end channels have an end portion which is angularly positioned with respect to the rest of the channels so that there exists a slight difference in longitudinal pitch at point 14 along the rolls 7 and 8. This change in pitch separates the bottoms of adjacent cases enough so that protruding flaps will not hold up flaps on the preceding case and the outside flaps will always be free to drop without interference from other cases.

The rolls 7 and 8 and accompanying channels are supported by a number of members 15, 16 and 17 (only member 15 being shown for rolls 7), and these members are slidably mounted on a base frame 18. The members 15 and 16 supporting each of the rolls are connected together by a section 19 having a central threaded opening 20. The tilted rolls 7 and 8 can be spaced apart in the transverse direction by the rotation of cranks 21 (only one of which is shown) pivotally mounted on opposite sides of frame 18. The screws 22 attached to each crank 21 pass through threaded openings 20 and are rotated by the cranks 21 to bodily move the members 15, 16 and 17 and the rolls 7 and 8. Thus, the space between the rolls can be adjusted so that the rolls can receive cases of various width. The rolls can be locked in adjusted position by lock nuts 23. A pair of guide rods 24 and 25 are mounted on channels 10 and 11 respectively by means of collars 26 welded to the ends of the channels and by rods 27 passing through these collars. The space between the rods 24 and 25 can be adjusted by movement of rods 27 through collars 26 in order to regulate the height and the level of the bottom of the cases resting on rolls 7 and 8.

During the movement of a case over rolls 7 and 8, the outside flaps will drop down against the rolls and the tilted plow 28 will pass above the outside flaps and will support the inner flaps as the case moves off of the rolls. The plow 28 is tilted somewhat downwardly so that as the case moves along the plow, the plow will force the empty containers back up into their normal position in the case. The case will then be pushed along plate 29 by following cases and will move along on its bottom inside

flaps. During this time the outside flaps will come into contact with the plow plows 30 and 31 and the outside flaps will be lifted upwardly into position to be grasped by the operator. These plow plows are in the form of a helix 5 so that the flaps will be gradually raised during movement of the case. The cases will be guided along plate 29 by guide rods 24 and 25 and a limit switch 32 is attached to rod 24 by means of a rod 33 which is supported by collar 34. This limit switch has an arm 35 which, when contacted by a case, will stop the conveyor 9 so that the cases will no longer be moved along plate 29. The position of arm 35 can be adjusted along rod 24 to allow for the coast of the cases imparted by conveyor 9. After the operator has removed the case of empty containers 10 from plate 29, the switch 32 will allow the conveyor 9 to push the next case into position to be lifted off by the operator. The entire uncasing unit is supported by a stand which is comprised of legs 36 and 37 and a cross member 38.

20 The operator 2 will manually move the case from uncaser unit 1 into position over the unscrambler conveyor 39 and will allow the empty containers to drop out of the bottom of the case onto the conveyor and thereby open the bottom inside flaps. The operator will lift the 25 case by grasping the outside bottom flaps which have been turned completely up and by pressing these flaps against the sides of the case. The empty containers will pass through unscrambler 40 and will be moved by conveyor 40' to the filling machines. The operator then 30 will place the empty case into position over a case load of filled containers accumulated in the caser unit 4. The caser unit 4 (see Figures 4 and 5) has a conveyor 41 driven by motor 42 which moves the filled containers onto a plate 43 which has a series of longitudinal slits. Two 35 arms 44 (only one of which is shown in Figure 5) are positioned on opposite sides of plate 43 and are pivotally mounted at one end at pivot points 45. These arms support a series of guides 46 which serve as guides for the containers leaving the conveyor 41. Two of these guides 40 are integral with arms 44 while the remainder are secured to the arms at a position in front of plate 43 so that they can pivot up and down in the slits in the plate 43. As shown in Figure 4, there are five guides 46 mounted by arms 44 and the three center guides move in three slits in plate 43.

45 A pair of casing arms 47 project upwardly from two of the guides 46 and then backwards toward conveyor 41 at their outer ends. Also, a stop 48 is carried by the arms 44 and is positioned between the end of plate 43 and the adjacent edge of dead plate 49. With the arms 47 in the upward position, filled containers can leave conveyor 41 and move between guides 46 until the leading containers hit stop 48. Additional containers will move up against the leading containers and load onto plate 43 a full case load of filled containers in the manner illustrated in Figure 4 (wherein a full case load comprises 50 12 containers). A pair of lever arms 49' (only one of which is shown in Figure 5) are pivotally mounted on opposite sides of plate 43 by brackets 50. The longer sections of arms 49' carry four stops 51 which are positioned to project upwardly through holes in plate 43 and between guides 46. These longer sections also mount a counterweight 52 which normally holds the stops 51 below the plate 43. A rod 53 is secured to the shorter sections of lever arms 49 and projects completely across the bottom of plate 43.

55 Referring to Figure 5, when the operator presses an empty case over a load of filled containers resting on plate 43, he will force the arms 47 downwardly and move the guides 46 out of the slits in plate 43. This results because the casing arms 47 in the up position cover a portion of the last row of containers which complete the full case and by pivoting the arms 47 downwardly, they will move out of the way of this last row and allow the empty case to pass downwardly. As the guides

46 move downwardly, they strike the rod 53 and cause the stops 51 to move up through the holes in plate 43 and in front of the filled containers which are not covered by the empty case. This prevents additional filled containers from moving on to plate 43 during the casing operation. Also, as the guides 46 move downwardly, the stop 48 is also moved from between plate 43 and dead plate 49 to allow the operator, after he has passed the empty case around the filled containers, to move the case forward from plate 43 to plate 49. As soon as the filled case is on dead plate 49, the guides 46 and arms 47 will be moved upward by counterweight 52 acting through rod 53, and at the same time the stops 51 will drop away from plate 43. The plate 43 will then be in condition to receive a new case of filled containers and these filled containers will move forward until the first row of containers strikes the stop 48 where they will be in a position to again be cased by the operator.

As the filled case is moved onto dead plate 49, it will be engaged by side conveyors 54 and 55 which are driven by motors 56 and 57 respectively. At this time the inside bottom flaps 58 will drop down along the edges of plate 49 while the outside bottom flaps 59 will be lying along plates 43 and 49. As the case is moved along plate 49 by conveyors 54 and 55, the inside bottom flaps 58 engage helical flap plows 60 and 61 which fold the inside flaps underneath the case as it moves from plate 49 onto conveyor 62. The end of plate 49 is formed into shoe 63 which allows the inside flap to come up to the bottom of the case and against the filled containers prior to moving onto conveyor 62. A slight space is left between shoe 63 and the edge of the conveyor 62 for this purpose. The side conveyors are mounted by a frame 64 and the plows 60 and 61 are secured by brackets to this frame.

The roll conveyor 62 moves the filled cases in a direction at right angles to their movement by the side conveyors and is wide enough to support one of the outside flaps which precedes the case on to the conveyor. From conveyor 62, the cases move onto conveyor belt 65 and the outside flaps are open. A motor 66 serves to drive both the roll conveyor 62 and the belt conveyor 65 and each of these conveyors is supported by individual frames. The gluing rolls 67 and 68 are on opposite sides of the conveyor 65 and are rotated in glue pans 69 and 70 respectively by motor 66. A pressure roller 71 is mounted above each of the rollers 67 and 68 and guide plates 72 and 73 are mounted on the glue pans 69 and 70 respectively and in position to direct the outside bottom flaps of the filled case between the glue rolls and the pressure rolls in order to apply a coat of glue to the outside flaps.

After the coat of glue has been applied to the outside 65 onto dead plate 74 where it is pushed along by succ-bottom flaps, the container is moved by belt conveyor ceeding cases. A pair of guide rods 75 and 76 extend from the end of the plate 74 back to the end of conveyor 62 and are spaced apart the width of a case so that the cases will follow the guide rods and remain on the conveyors and the plate. These guide rods are supported by brackets 77 which are secured to the frames for plate 74 and conveyor 62.

As the filled case moves along the plate 74, the inside flaps will be underneath the case and the outside flaps will engage the helical flap plows 78 and 79 which are supported by the rods 75 and 76 respectively. These plows will serve to turn the outside flaps underneath the filled case as they move off the shoe 74' at the end of plate 74, and onto the belt conveyor 80 which is driven by motor 81. The shoe 74' is spaced somewhat from the end of conveyor 80 to allow for this action. When the filled cases arrive on conveyor 80, the outside flaps will be held in position by the weight of the containers in the case of a sufficient time to allow the glue to set and by such time, the cases can be set on pallets or oth-

erwise stored without danger of the cases becoming un-glued.

When the subject invention is placed in operation, cases containing empty containers will move along conveyor 9 and the bottoms of these cases will be folded in the usual way but will be unsealed. The empty containers will be rightside up in the case, and the junction of the bottom outside flaps will be positioned in the direction of movement of the conveyor. As the cases move onto the rolls 7 and 8, the outside bottom flaps will drop down onto the rolls and will be moved away from the bottom of the cases by shoe 28 as the cases pass onto dead plate 29. The flap plows 30 and 31 are in the form of a helix and will lift the outside flaps upwardly in the manner illustrated in Figure 3 as the cases move to the end of plate 20.

At this time the operator 2 will lift the case and empty containers from the plate 29 and move the case over conveyor 39. The empty containers will be allowed to drop out, rightside up onto the conveyor 39 and pass through unscrambler 40 and onto conveyor 40'. The operator will then move the empty case which is still right-side up into position over a case load of filled containers assembled on plate 43. Both the inside and outside bottom flaps of the container will be open and will allow the operator to pass the empty case down over the filled containers. After this is done the inside bottom flaps will drop over the sides of plate 43 and one of the outside bottom flaps will lie on dead plate 49.

At the time the empty case is placed over the filled containers, casing arms 47 will be lowered and thereby lower stop 48 to allow the operator to slide the case load of containers onto dead plate 49. The lowering of casing arms 47 will also cause stops 51 to rise into a position to prevent further filled containers from moving onto plate 43 while the operator is moving a filled case onto plate 49. After the filled case is on plate 49, the arms 47 will move upwardly and the stops 51 downwardly to allow additional filled containers to move onto plate 43 until the leading containers hit stop 48 and thereby a second case load of filled containers will immediately accumulate on plate 43. Since stop 48 is depressed during the time a filled case is moved onto plate 49, the stop 51 will be held in the up position to prevent other filled containers from moving onto plate 43 during this time.

The side conveyors 54 and 55 will move the filled case along plate 49 and at the same time the flap plows 60 and 61 will fold under the bottom inside flaps in the manner illustrated in Figure 6 as the container moves off of shoe 63. The conveyor 62 will then move the filled cases onto belt 65 where the outside flaps will be directed past the gluing rolls and will receive a coating of glue which will stick the flaps together but will not stick to the containers. The cases will then move onto plate 79 where the outside flaps encounter flap plows 78 and 79 which will fold the bottom outside flaps into position under the case in the manner illustrated in Figure 9 as the case moves off of shoe 74' and onto conveyor 80. The filled cases will then remain on the conveyor 80 for a sufficient time to allow the glue on the bottom outside flaps to set prior to stacking or loading the cases onto pallets. It is therefore apparent that during the operation of the subject invention, the cases at all times remain in the upright position and the bottom flaps are opened and closed mechanically. Also, since the empty and filled containers are always in the upright position, it is unnecessary to turn the cases or the containers during the uncasing and casing operations. Because of the fact that the unscrambler and caser units are located adjacent each other, it is not necessary to store or transport the empty cases between the uncasing operations although a chute 82 (Figure 1) can be provided for convenient storage of empty cases by the operator if such storage space is needed because of the lack

of filled containers. The schematic wiring diagram for the various motors is illustrated in Figure 10 and the switch 32 is shown in the circuit for motor 9.

This invention makes it possible to uncase and case the containers with a minimum of personnel, and it is contemplated that the one operator involved could be displaced by machinery to handle the functions described for the operator. However, the operator is desirable because some inspection of the cases and containers is usually necessary at the point where the operator is positioned. The reference to containers made herein contemplates containers made of any suitable material such as glass, metal, plastic, etc. and cases of any suitable material can also be used for these containers. It is understood that various other modifications are contemplated and may be readily resorted to by those skilled in the art without departing from the spirit and scope of the invention as hereinafter defined by the appended claims.

What is claimed is:

1. In a container uncaser, first means for conveying a case of empty containers, said case and containers being right side up with the bottom flaps of said container in position but unglued, said first means comprising a pair of conveyors inclined toward each other to allow a bottom edge of said case to roll along each of said conveyors, the weight of said containers being sufficient to force each bottom outside flap downwardly against one of said conveyors, supporting members for mounting each of said inclined conveyors in a manner that each conveyor has a slight difference in longitudinal pitch at the same position intermediate its ends in order to separate the bottom of said case from the bottom of the following case, and second means positioned at the end of said inclined conveyors to receive said case and plow said outside flaps away from the bottom of said case.

2. A container caser comprising first means for receiving a case load of containers, second means mounted for up and down movement with respect to said first means, said second means mounting a series of container guides to guide said containers onto said first means in rows when said second means is in the up position, a stop carried by said second means for collecting said containers on said first means when said second means is in the up position, one or more casing arms carried by said second means in position to be moved downwardly by an empty case as said case is positioned over a case load of containers accumulated by said first means, said second means being moved downwardly to its down position by said arms to lower said guides and said stop so that said filled case can be moved off said first means while the bottom flaps of said filled case are open.

3. A container caser as defined in claim 2 having third means for supporting said filled case as said case is manually moved off said first means without turning said case, side conveyor means for receiving said filled case from said third means and forceably moving said case along said third means, and fourth means associated with said side conveyor means for plowing under the inside bottom flaps of said case into closed position as said case is moved by said conveyor means, said inside bottom flaps being thereafter retained in closed position by the weight of said containers.

4. A container caser as defined in claim 3 having conveyor means for receiving said filled case from said side conveyor means without turning said case and moving said filled case at right angles to its movement by said side conveyor means, fifth means associated with said conveyor for applying glue to said outside bottom flaps and sixth means for plowing under said outside bottom flaps into closed position, said outside bottom flaps being retained in closed position by the weight of said containers.

5. A container caser and case sealer comprising first means for moving a case of containers with both the case and containers right side up while said inside and outside

bottom flaps are open, second means associated with said first means for plowing under said inside bottom flaps into closed position, third means for receiving said case of containers from said first means without turning said case and thereafter moving said case at right angles to its movement by said first means, fourth means associated with said third means for applying glue to the outside bottom flaps, and fifth means for plowing under the outside bottom flaps into closed position after said case leaves said third means, said inside and outside bottom flaps being held in closed position after being plowed under by the weight of the containers in said case.

6. In a device for casing filled containers, means for conveying filled containers in a case having its inside and outside bottom flaps open, means for turning under said inside bottom flaps while said case is being moved by said conveyor means, means for moving said case in a direction at right angles to said conveying means with its inside bottom flaps closed and its outside bottom flaps open, means for applying glue to said outside bottom flaps during movement by said moving means and means for thereafter turning under said outside bottom flaps.

7. A method of casing filled containers which comprises placing the open bottom of an empty case over a case load of filled containers on a conveyor with the outside bottom flaps lying on said conveyor, turning under the inside bottom flaps during movement on said conveyor, moving said case and containers on a second conveyor placed at right angles to said first conveyor, applying glue to the bottom outside flaps and thereafter turning under said outside flaps during movement on said second conveyor.

8. In a container uncaser, first conveyor means for conveying a case of empty containers, said case and containers being right side up with the bottom flaps of said container in position but unglued, second conveyor means comprising a pair of conveyors inclined toward each other and positioned to receive said case from said first conveyor means, said containers being of sufficient weight to force each outside flap downwardly against one of said inclined conveyors, flap turning means positioned at the end of said inclined conveyors to receive said case and turn said outside flaps away from the bottom of said case and switch means mounted on said flap turning means to prevent movement of said first conveyor means so long as a case remains on said flap turning means.

9. A container caser comprising first means for receiving a case load of containers, second means mounted for up and down movement with respect to said first means, said second means mounting a series of container guides to guide said containers onto said first means in rows when said second means is in the up position, a stop carried by said second means for collecting said containers on said first means when said second means is in the up position, one or more casing arms carried by said second means in position to be moved downwardly to its down position by said arms to lower said guides and said stop so that said filled case can be moved off said first means while the bottom flaps of said filled case are open, and means movable by said second means for preventing said containers from moving onto said first means while said second means is in its down position.
